The ornamental design for a liquid sampling and detecting device, as shown.

DESCRIPTION

FIG. 1 is a perspective view of a liquid sampling and detecting device showing my new and ornamental design;

FIG. 2 is a front view thereof, the rear view being a mirror image thereof;

FIG. 3 is a top view thereof;

FIG. 4 is a bottom view thereof;

FIG. 5 is a side view thereof, an opposite side view being a mirror image thereof;

FIG. 6 is another perspective view, showing an alternative position of the liquid sampling and detecting device where a lid of the device is open;

FIG. 7 is a front view thereof, the rear view being a mirror image thereof;

FIG. 8 is a top view thereof;

FIG. 9 is a bottom view thereof;

FIG. 10 is a side view thereof, an opposite side view being a mirror-image thereof;

FIG. 11 is a perspective view of a transparent bottle of the device;

FIG. 12 is a front view of the bottle, the rear view being a mirror image thereof;

FIG. 13 is a top view thereof, the bottom view being a mirror image thereof;

FIG. 14 is a side view thereof, the opposite side view being a mirror-image thereof;

FIG. 18 is a side view thereof, the opposite side view being a mirror image thereof;

FIG. 19 is a perspective view of the transparent lid;

FIG. 20 is a rear view of the lid, the front view being a mirror image thereof;

FIG. 21 is a side view of the lid, the opposite side view being a mirror image thereof;

FIG. 22 is a perspective view of an insert of the device;

FIG. 23 is a front view thereof;

FIG. 24 is a rear view thereof;

FIG. 25 is a top view thereof;

FIG. 26 is a bottom view thereof;

FIG. 27 is a side view thereof, the opposite side view being a mirror image thereof;

FIG. 28 is a section view along Lines 28-28 in FIG. 22;
FIG. 29 is another perspective view of the insert with testing
strips mounted therein;
FIG. 30 is a rear view thereof;
FIG. 31 is a top view thereof;
FIG. 32 is a bottom view thereof;
FIG. 33 is a side view thereof, the opposite side view being a
mirror image thereof;

FIG. 34 is a perspective view of a handle of the device;
